UNITED STATES PATENT OFFICE

GERALD L. BRENNAN, OF DETROIT, MICHIGAN, ASSIGNOR TO PHILLIPS PETROLEUM COMPANY, OF BARTLESVILLE, OKLAHOMA, A CORPORATION OF DELAWARE

GAS BURNER EQUIPMENT

Application filed July 3, 1930. Serial No. 465,752.

This invention relates to gas burners, and more especially to novel devices for use in burning normally gaseous paraffin hydrocarbons and air.

5 At the present time, it is customary to extract from natural gas, commercial butane, and to mix the same with air before burning the mixture in a gas stove or the like. It has been found that ordinary gas stove equipment is not especially suitable for this purpose, and one of the salient objects of the present invention is to provide the cocks of such a gas stove with velocity reducing spuds to obtain maximum efficiency from the 15 burners.

The combustion characteristics of butane-air carbureted gas are similar to those of natural gas, since natural gas is composed principally of the paraffin hydrocarbon, 20 methane. The molecular formula for butane is C_4H_{10} . The combustion of butane is represented by the following chemical equation:

25 It will be noted from the above that 1 part of butane vapor requires 31.1 parts of air ($6.5O_2 + 24.6N_2$) for theoretically complete combustion.

30 1 cu. ft. of butane vapor in a 530 B. t. u. butane-air mixture is already accompanied by 5.08 cu. ft. of air as it issues from the spud. 26.02 additional cu. ft. of air per cu. ft. of butane vapor must eventually be added 35 for perfect combustion. Ordinarily the total amount of air in the mixture issuing from burner ports on domestic appliances should be about 60% of the theoretical amount required for complete combustion, the remainder 40 being supplied as secondary air at the burner ports. 31.1 cu. ft. air $\times$ 60% primary air used = 18.66 cu. ft. air which should, on the average, accompanying 1 cu. ft. of butane vapor as primary air. 5.08 cu. ft. are already 45 in the butane-air gas mixture leaving 13.58 cu. ft. air per cu. ft. butane vapor, to be inspirited in the burner throat.

This amount is easily inspirited inasmuch as the high specific gravity of the butane-air mixture (1.16 air equalling 1.0) greatly in-

creases the energy of the gas stream over that of the same volume of ordinary manufactured gas. As a matter of fact, with ordinary air shutters, it is sometimes impossible to control the primary air supply with any degree of 55 accuracy as very slight movements of the shutters disturb the gas air ratio, and throw the flame out of adjustment. Shutters almost completely closed, also collect lint and dust, which will eventually produce very unsatisfactory combustion conditions. 60

There are three ways of overcoming this difficulty:

1st. By the use of special air shutters with ground faces and restricted openings. This 65 method has many obvious disadvantages as it imposes extra expense upon the manufacturer and, in case of converted appliances, is not at all feasible.

2nd. By using a double adjustable valve 70 which controls the volume as well as the velocity of the gas entering the burner throat. This valve, when properly adjusted, works very satisfactorily and permits the shutter to be placed in a wide open position. The 75 amount of primary air induced is, of course, greatly reduced. Such a valve is more expensive than the ordinary stove cock, and its use on converted appliances is hardly feasible on account of cost and time required for 80 the change.

3rd. By the use of my velocity reducing spud. Such spud is designed to (a) deliberately cut down the exit velocity of the flowing gas stream, and (b) to change the location of the discharge into the Venturi mixing tube throat, thereby reducing the efficiency of the mixing tube as an air inspirating device, and making the accurate control of primary air more simple. A partial opening 85 of the air shutter is permitted, and a wider and more precise range of air adjustment results, due to the lowered differential pressure across the air shutters. 90

95 My spuds are especially efficient for stove top burners. This spud can be used on conventional adjustable or fixed spud cocks for open or closed manifold stoves, and is low in cost, quickly installed, and permanent in its effect on the burner functions. When used 100

on converted appliances, it is of particular advantage.

With the foregoing object outlined and with other objects in view which will appear as the description proceeds, the invention consists in the novel features hereinafter described in detail, illustrated in the accompanying drawings, and more particularly pointed out in the appended claims.

10 Referring to the drawings,

Fig. 1 is a side view partly in longitudinal vertical section, of a conventional fixed orifice cock, and air mixing tube, combined with one form of the improved spud.

15 Fig. 2 is a plan view of a burner to which the gaseous mixture is furnished by the air mixing tube.

Fig. 3 is a view similar to Fig. 1, but showing another form of the spud applied to an 20 adjustable orifice cock.

Fig. 4 is an enlarged longitudinal sectional view of the spuds shown in Fig. 1.

Fig. 5 is an end view of the same.

25 Figs. 6 and 7 are a longitudinal sectional view and an end view, respectively, of the spud shown in Fig. 3.

Fig. 8 is a vertical sectional view on the line 8—8 of Fig. 1.

In the embodiment of the invention illustrated in Figs. 1, 2, 4, 5 and 8, the gas supply pipe is designated 8, and it is connected in the usual manner to an ordinary fixed orifice cock 9, which discharges the gas into an air mixing tube 10 that leads to the burner 11.

30 At 12, the conventional air controlled damper shutters are arranged, through which the primary air is induced to flow by the passage of the gas stream from the cock into the air mixer.

35 In accordance with the present invention, a special type of imperforate velocity reducing spud 13 is connected to the outlet end of the cock, and the outer end of this spud terminates at 14 at a point within the cylindrical

40 restricted portion 15 of the air mixing tube, that is, just beyond the line where the flared portion 16 merges into the cylindrical portion 15.

45 From Fig. 4 it may be seen that the spud is screw-threaded at its inner end as at 17, to allow the same to be screwed into the outlet end of the cock, and forwardly of the screw-threaded portion, an angular surface 18 is provided to facilitate the turning of the spud by a wrench or the like.

50 The bore of the spud forms a Venturi throat or fixed orifice 19 adjacent the outlet end of the cock, and from this throat, the bore is cylindrical to the outer end 14 of the spud, to allow expansion of the gas stream.

55 This special internal shape of the spud reduces the velocity of the gas stream flowing through the same, and as the end 14 projects into the cylindrical portion of the bore of the air mixing tube, the gas stream dis-

charged from the spud will entrain just the right amount of primary air, and the mixture will be a proper one to admix with the secondary air at the burner 11.

Instead of applying the invention to stoves employing fixed orifice cocks, the same principle may be embodied in a spud designed for use with a conventional adjustable orifice cock 20 of the type shown in Fig. 3. In this case, the ordinary adjustable members on the outlet end of the cock will be removed, and in their place, the imperforate spud 21 will be inserted, which spud is of the velocity reducing type, and terminates at 22 within the cylindrical restricted portion 23 of the air 75 mixing tube.

80 As best shown in Figs. 6 and 7, this type of spud has internal screw threads 24 for engagement with the apertured outlet point 25 of the cock, and to facilitate turning of the spud, the latter is provided with a hexagonal surface 26. Here also the spud has a Venturi throat 27 which merges into a cylindrical bore 28 of about half the length of the spud.

85 In each instance, the spud cuts down the exit velocity of the flowing gas stream, and also changes the location of the discharge point of the gas stream into the Venturi mixing tube throat, and consequently, reduces the efficiency of the mixing tube as an air inspirating device. It also makes the accurate control of primary air easier and simpler, and of course, a partial opening of the air shutter 12 is permitted, and a wider and more precise range of air adjustment results, due to the lowered differential pressure 90 across the air shutters.

95 While the invention is especially suitable for use with normally gaseous paraffin hydrocarbon fuels, it will be apparent to those familiar with such devices, that it also may be used with other types of gaseous fuels.

100 While preferred embodiments of the invention have been disclosed herein, in such manner that the same may be readily understood by those skilled in the art, it is apparent that changes may be made in the details disclosed, without departing from the spirit of the invention, as expressed in the claims.

105 What I claim and desire to secure by Letters Patent is:

110 1. In gas burning equipment, a gas cock having an outlet, a Venturi air mixer into which the outlet extends, means for admitting air into the mixer adjacent to the point where the cock outlet enters the same, and a velocity reducing spud connected to the outlet of the cock and projecting into the reduced portion 115 of the throat of the air mixer.

120 2. In gas burner equipment, an air mixer tube having a flared end portion provided at its extremity with means for admitting air into the tube, a gas cock having an outlet extending through the extremity into the tube,

- and a velocity reducing spud connected to the outlet of the cock and projecting through the flared portion of the tube into the restricted portion of the latter.
- 5 3. In gas burner equipment, an air mixer tube having a flared end portion provided at its extremity with means for admitting air into the tube, a gas cock having an outlet extending through the extremity into the tube, a velocity reducing spud connected to the outlet of the cock and projecting through the flared portion of the tube into the restricted portion of the latter, and a damper for controlling the air admission means of said tube.
- 10 4. In gas burner equipment, an air mixer tube having a flared end portion provided at its extremity with means for admitting air into the tube, a gas cock having an outlet extending through the extremity into the tube, and a velocity reducing spud connected to the outlet of the cock and projecting through the flared portion of the tube into the restricted portion of the latter, said spud having a Venturi shaped surface in its bore.
- 15 5. In gas burner equipment, an air mixer tube having a flared end portion provided at its extremity with means for admitting air into the tube, a gas cock having an outlet extending through the extremity into the tube, and a velocity reducing spud connected to the outlet of the cock and projecting through the flared portion of the tube into the restricted portion of the latter, said spud having a Venturi shaped surface in its bore,
- 20 30 35 40 45 50 55 60 65
- 80 85 90 95 100 105 110 115 120 125 130
6. In gas burner equipment, an air mixer tube having a flared end portion provided at its extremity with means for admitting air into the tube, a gas cock having an outlet extending through the extremity into the tube, and a velocity reducing spud connected to the outlet of the cock and projecting through the flared portion of the tube into the restricted portion of the latter, said spud being joined to the cock by a threaded connection and having a Venturi throat arranged in close proximity to the outlet of the cock, the portion of the spud bore between the Venturi surface and the outer end of the spud being enlarged and of substantially uniform cross section throughout its length.
7. In gas burner equipment, a gas cock having a threaded outlet, and an imperforate spud having threads engaging the threads of the outlet, said spud having a Venturi throat positioned in close proximity to the extremity of the cock to receive a gaseous mixture from the latter, the portion of the spud bore between the throat and the outer extremity of the spud being enlarged and substantially cylindrical.
8. In gas burner equipment, a velocity reducing spud having one of its end portions threaded for connection to a gas cock and provided with an angular external surface to facilitate turning of the spud by a suitable tool, the spud being imperforate and its bore having a Venturi shaped surface, the portion of the bore between said Venturi shaped surface and the outer end of the spud being enlarged and of substantially uniform cross-sectional area throughout its length.
- In testimony whereof, I hereto affix my signature.
- GERALD L. BRENNAN.
